UNITED STATES PATENT OFFICE.

HARLEY T. PROCTER, OF CINCINNATI, OHIO.

DESIGN FOR A CAKE OF SOAP.

Specification forming part of Design No. 11,365, dated August 26, 1879.

To all whom it may concern:

Be it known that I, HARLEY T. PROCTER, of Cincinnati, county of Hamilton, and State of Ohio, have invented a new, useful, and ornamental Design for the Configuration of Cakes of Soap, of which the following is a specification.

The nature of my design is shown in the accompanying drawings, to which reference is made.

Figure 1 is a perspective. Fig. 2 is a longitudinal horizontal section showing the outline of one side of the cake, the other side, which is the same in outline, being broken off.

The cake is substantially rectangular in each of its surfaces. The upper and under surfaces are surrounded by a raised border, as shown in Fig. 1. This border is divided by depressions extending to the plane of the sunken surface, or substantially so, the outline of the sides of these depressions being symmetrical with the lateral edge of the border. Corresponding depressions of substantially the same depth extend down the sides of the cake, connecting the depressions in the border of the upper side with those of the underside. This construction serves to diversify each of the longer and otherwise flat surfaces of the cake

by waves or curves, and enables me to make long cakes having a sunken surface for the lettering without the monotonous brick-like appearance it must otherwise have. The depressions also mark convenient divisions into which the cake may be divided for use, and in connection with the corresponding symmetrical borders enabling the cakes into which it is subdivided to retain an ornamental and substantially complete appearance, while relieving them from the disfigurement and inconvenience of sharp or unfinished edges at the place of division. The name of the manufacturer may be stamped on one of the sunken surfaces and the name of the soap on the other; or these or any other device may be stamped in alternate divisions of both sides. In either case the raised border serves to protect them.

I claim—

The herein-described design or configuration of the cake of soap, consisting of the main portion and the raised border provided with the depressions in border and sides symmetrical with the lateral edge of said border.

HARLEY T. PROCTER.
